5 SHEETS—SHEET 1.

A hand-drawn electrical circuit diagram. At the bottom left is a power source symbol with two output lines labeled 100 and 109. A switch is connected in parallel with the 100 line. The 100 line then connects to a relay coil (indicated by a rectangle with a vertical bar). The normally open contact of this relay is connected to the 109 line. The 109 line then enters a logic board. The logic board has four vertical columns of contacts, labeled 0, 1, 2, 3, 4, 5, 6, 7, 8, 9 from bottom to top. The 109 line connects to contact 0. The 100 line connects to contact 1. The 109 line also connects to contact 2. The 100 line connects to contact 3. The 109 line connects to contact 4. The 100 line connects to contact 5. The 109 line connects to contact 6. The 100 line connects to contact 7. The 109 line connects to contact 8. The 100 line connects to contact 9. The logic board has a vertical line labeled 105 connecting to contact 9. From contact 9, a line goes up to a junction point. From this junction point, lines branch out to various components: 1) a junction point labeled 101, 2) a junction point labeled 111, 3) a junction point labeled 102, 4) a junction point labeled 103, 5) a junction point labeled 104, 6) a junction point labeled 105, 7) a junction point labeled 106, 8) a junction point labeled 107, 9) a junction point labeled 108, 10) a junction point labeled 109, 11) a junction point labeled 110, 12) a junction point labeled 111, 13) a junction point labeled 112, 14) a junction point labeled 113, 15) a junction point labeled 114, 16) a junction point labeled 115, 17) a junction point labeled 116, 18) a junction point labeled 117, 19) a junction point labeled 118, 20) a junction point labeled 119, 21) a junction point labeled 120, 22) a junction point labeled 121, and 23) a junction point labeled 122.

UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,337,715.

Specification of Letters Patent. Patented Apr. 20, 1920.

Application filed April 13, 1918. Serial No. 228,413.

To all whom it may concern:

Be it known that I, JAMES L. MCQUARRIE, a citizen of the United States, residing at Montclair, in the county of Essex, State of New Jersey, have invented certain new and useful Improvements in Telephone Systems, of which the following is a full, clear, concise, and exact description.

This invention relates to telephone systems and more particularly to telephone systems employing machine switching.

The object of this invention is to provide means whereby automatic switches employed in such systems may be controlled by means of currents of different frequencies.

In accordance with this object one feature of the invention is the provision of means for varying the impedance of a circuit so as to cause a current of a particular intensity to flow through the circuit at different frequencies.

In accordance with this object, another feature of this invention is the provision of means which is operated by the various currents to selectively control the operation of automatic switches.

Other features of the invention will appear from the following specification and claims.

Referring now to the drawings, Figures 1, 2, 3, 4 and 5, when placed together with Fig. 2 to the right of Fig. 1, Fig. 3 below Fig. 2, and Figs. 4 and 5 to the right of Figs. 3 and 2 respectively, form a portion of a telephone system embodying the features of this invention. Fig. 1 represents a calling substation and a line finder switch; Fig. 2 represents a district selector switch; Fig. 3 represents a trunk finder switch and a set of counting relays; Fig. 4 represents registers which, through the trunk finder switch and counting relays, are instrumental in extending a call through the district selector switch and other switches, and Fig. 5 represents circuits which are controlled by the calling subscriber to set the registers shown in Fig. 4.

In a number of the drawings, sequence switches such as 200 in Fig. 2, are shown. These switches are substantially of the construction disclosed in Patent No. 1,127,808, issued February 9, 1915 to J. N. Reynolds and C. F. Baldwin. The type of selector switch and trunk finder switch shown is sub-

stantially of the construction disclosed in Patent No. 1,177,044, issued March 28, 1916 to James L. McQuarrie.

Referring now especially to Fig. 1, we will assume a call to be initiated by the subscriber at substation 100. The action of this subscriber in removing his receiver from its switchhook results in the operation in the well-known manner, of the line finder switch 101. As soon as the brushes 102, 103 and 104 of the line finder switch reach the terminals 105, 106 and 107 respectively of the calling line, a circuit is closed from grounded battery, through the lower left-hand winding of repeating coil 201 (Fig. 2), 70 winding of supervisory relay 202, right-hand contact of sequence switch spring 203, conductor 204, brush 103, terminal 106, conductor 108, normal contacts of keys 4, 3, 2, 1 and 0 in series, conductor 109, loop at substation 100, conductor 110, normal contacts of keys 5, 6, 7, 8 and 9 in series, conductor 111, terminal 107, brush 104, conductor 205, upper contact of sequence switch spring 206, upper left-hand winding of repeating 80 coil 201 to ground. Supervisory relay 202 becomes energized and closes a circuit from grounded battery, through the armature and contact of relay 202, conductor 207, brush 102, terminal 105, winding of relay 112 to 85 ground. Relay 112 becomes energized and stops, in the well-known manner, further movement of the line finder switch 101. A circuit is also closed in parallel with relay 112 through the winding of relay 208 to 90 ground. Relay 208 becomes energized and closes a circuit from grounded battery, through the power magnet of sequence switch 200, upper left-hand contact of sequence switch spring 209, right-hand armature and front contact of relay 208 to ground for moving the sequence switch 200 out of position 1 and into position 2. Relay 208 also completes a locking circuit for itself and for relay 112 by closing a circuit from 95 grounded battery, contact of sequence switch spring 211, left-hand armature and front contact of relay 208 to ground through the windings of relays 208 and 112 in parallel.

When the sequence switch 200 reaches position 2, a circuit is completed from grounded battery, through the power magnet of sequence switch 300 (Fig. 3), upper right-hand contact of sequence switch spring 301, conductor 302, lower contact of sequence 100 110

switch spring 210 to ground, for moving the sequence switch 300 out of position 1 and into position 2.

In position 2 of the sequence switch 300, a circuit is completed from grounded battery, through the winding of the updrive magnet 303, contact of sequence switch spring 304, right-hand armature and back contact of relay 305, to ground. Magnet 303, upon attracting its armature, forces the driving ribbon 306 of the cord finder switch against the constantly rotating roller 307, whereby the brush carriage 308 is elevated. The brushes 309, 310, 311, 312 and 313 move over and make contact with the associated terminals 314, 315, 316, 317 and 318 respectively. When the brush 309 engages the terminal 314 connected to the trunk circuit associated with the line finder 101, a circuit is closed from grounded battery, through winding of relay 305, left-hand contact of sequence switch spring 319, brush 309, terminal 314, conductor 320, upper left-hand contact of sequence switch spring 210 to ground. Relay 305 becomes energized and closes a locking circuit for itself from grounded battery, through the winding of relay 305, right-hand contact of sequence switch spring 319, left-hand armature and contact of relay 305, brush 310, terminal 315, conductor 321, upper right-hand contact of sequence switch spring 210 to ground. Relay 305 by attracting its right-hand armature opens at its back contact the energizing circuit of the updrive magnet 303 to stop further upward movement of the brush carriage 308, and closes at its front contact a circuit from grounded battery, through power magnet of sequence switch 300, lower left-hand contact of sequence switch spring 301, right-hand armature and front contact of relay 305 to ground, for moving the sequence switch 300 out of position 2 and into position 3.

As soon as the sequence switch 300 reaches position 3, a circuit is completed from positive pole of battery, upper secondary winding of transformer 501, lower secondary winding of transformer 501, (Fig. 5), right-hand winding of relay 502, conductor 503, upper contact of sequence switch spring 322, brush 312, terminal 317, conductor 324, left-hand contact of sequence switch spring 208, over the line circuit previously described to the lower contact of sequence switch spring 206, then through conductor 325, terminal 318, brush 313, upper contact of sequence switch spring 323, conductor 504, left-hand winding of relay 502, conductor 506, to negative pole of battery. Relay 502 energizes and closes a circuit for relay 507 from grounded battery, through winding of relay 507, armature and front contact of relay 502, to ground. Relay 507 by attracting its left-hand armature opens the

circuit of release relay 526 and thereby prevents this relay from energizing and causing the trunk finder switch to be restored upon the sequence switch 300 arriving in position 3.

Five sources of alternating current f^1 , f^2 , f^3 , f^4 and f^5 each being of the same potential but of a different frequency, are inductively connected to the two secondary windings of the transformer 501. In accordance with the well-known laws of induction, each one of these sources of current will induce an electromotive force of the same frequency in each of the secondary windings of the transformer. The secondary windings are made substantially the same and therefore the electromotive forces induced in each winding are the same. In the above traced circuit, the secondary windings are connected together differentially, and as a result of this fact the electromotive forces induced in one of the windings exactly neutralize the corresponding electromotive forces induced in the other of said windings, so that no alternating current flows at this time in such circuit.

The circuits are now in condition for the calling subscriber to start operating his call transmitter. The preferred form of call transmitter is shown in Fig. 1, which consists of a set of ten keys situated at the calling substation. The conductors 111 and 110 of one side of the line circuit are connected together by two parallel paths, one through the normal contacts of five of the keys in series, such as keys 5 to 9, inclusive, and the other through the inductance 123. The conductors 108 and 109 of the other side of the line circuit are also connected together by two parallel paths, one through the normal contacts of the other five keys in series such as keys 0 to 4, inclusive, and the other through the inductance 124. An inductance 113 and a capacity 114 are connected to two keys such as keys 4 and 9. A different inductance 115 and a different capacity 116 are connected to two other keys such as keys 3 and 8. Similarly, different inductances 117, 119 and 121 and capacities 118, 120 and 122 are connected to keys 2 and 7, keys 1 and 6, and keys 0 and 5, respectively.

The alternate contacts of keys 5 to 9, inclusive, are connected in parallel to the conductor 108 so that whenever any one of these keys is operated the inductance and capacity connected to the operated key is connected to the conductor 108. At the same time the normal circuit over the calling line is interrupted and two other circuits are closed. One of these circuits extends from ground, through the lower secondary winding of the transformer 501, conductor 505, thence in parallel through relay 508 and condenser 513 in series, relay 509 and con-

denser 514 in series, relay 510 and condenser 515 in series, relay 511 and condenser 516 in series, relay 512 and condenser 517 in series, and the right-hand winding of relay 502 to the common conductor 503, then through the upper contact of sequence switch spring 322, brush 312, terminal 317, conductor 324, left-hand contact of sequence switch spring 203, conductor 204, brush 103, terminal 106, conductor 108, to ground through the alternate contact of the depressed key and the particular inductance and capacity connected thereto. The other circuit may be traced from ground, through the upper secondary winding of the transformer 501, battery, thence in parallel to the common conductor 504 through relay 518 and condenser 523 in series, relay 519 and condenser 524, relay 520 and condenser 525, relay 521 and condenser 526, relay 522 and condenser 527, and left-hand winding of relay 502, then through the upper contact of sequence switch spring 323, brush 313, terminal 318, conductor 325, lower contact of sequence switch spring 206, conductor 205, brush 104, terminal 107, conductor 111, inductance 123, loop at substation 100, conductor 109, normal contacts of keys 0 to 4 inclusive to ground through the alternate contact of the depressed key and the particular inductance and capacity connected thereto.

The relays 508 to 512 inclusive, and relays 518 to 522 inclusive are alternating current relays, each of which will not operate until a particular value of alternating current of a particular frequency flows through its winding. A current of a different frequency is required to operate each one of the relays 508 to 512 inclusive and similarly, a current of different frequency is required to operate each one of the relays 518 to 522 inclusive.

Each of the sources of current f^1 to f^5 induces an electromotive force of a corresponding frequency in each of the described circuits, and each of these induced electromotive forces causes a current of a corresponding frequency to flow through each of these circuits. The capacity and inductance of the first mentioned circuit are of such values that resonance occurs for one of the electromotive forces induced therein, thereby causing sufficient current of the corresponding frequency to flow through this circuit to cause the particular one of the relays 508 to 512 inclusive to operate, which operates at such frequency. The capacity and inductance of the first mentioned circuit are, however, of such values that they prevent sufficient current, produced by any of the other induced electromotive forces, from flowing through the circuit and operating any other one of the relays 508 to 512 inclusive. The particular one of the relays 508 to 512 inclusive which operates, controls a register in a manner hereinafter described.

The capacity and inductance of the second above traced circuit are of such values that none of the electromotive forces induced in the upper secondary winding of the transformer 501 produce sufficient current in this circuit to operate any of the relays 518 to 522 inclusive.

It will, therefore, be observed that by depressing a particular one of the keys Nos. 5 to 9 inclusive, electromotive forces of different frequencies are induced in two different circuits, each of which includes one side of the line connecting the calling substation to the central office. The impedance of one of these circuits is so designed that resonance occurs for one of the electromotive forces induced therein, which is of a particular frequency, and as a result of this, sufficient current flows at this particular frequency to operate a particular alternating current relay which controls the setting of the registers. This impedance, however, is such that it prevents sufficient current of any other frequencies from flowing through this circuit to operate any one of the other alternating current relays. The impedance of the other circuit closed by the depression of such key, is such as to prevent sufficient current of any frequency to flow through such circuit to operate any one of the alternating current relays therein.

By depressing any other one of the keys Nos. 5 to 9 inclusive, a different inductance and capacity is included in the above traced circuits.

The impedance of the first traced circuit will be changed each time a different key is depressed so that resonance will occur for a different one of the electromotive forces induced in the lower secondary winding of the transformer 501. Sufficient current of the corresponding frequency then flows through this circuit and operates the particular one of the relays 508 to 512 inclusive, which operates at such frequency. As before the new impedance of this circuit and the impedance of the second traced circuit, which is also changed each time a different key is depressed, are so designed that none of the other nine alternating current relays operate.

It will, therefore, be observed that the depression of a particular one of the keys Nos. 5 to 9 inclusive will cause a particular one of the relays 518 to 522 to operate.

The alternate contacts of keys Nos. 0 to 4 inclusive, are connected in parallel to the conductor 110 so that whenever any one of these keys is operated such contact is connected to the conductor 110. At the same time the circuit through the normal contacts of keys Nos. 0 to 4 inclusive, is opened and thereby the normally closed shunt circuit around the inductance 124 is broken.

The normal circuit over the calling line 130

is thereby interrupted and two other circuits are closed. One of these circuits extends from ground, through the lower secondary winding of the transformer 501, conductor 5 505, thence in parallel to the common conductor 503, through relay 508 and condenser 513 in series, relay 509 and condenser 514 in series, relay 510 and condenser 515 in series, relay 511 and condenser 516 in series, 10 relay 512 and condenser 517 in series, and the right-hand winding of relay 502, then through the upper contact of sequence switch spring 322, brush 312, terminal 317, conductor 324, left-hand contact of sequence 15 switch spring 203, conductor 204, brush 103, terminal 106, conductor 108, inductance 124, conductor 109, loop at substation 100, conductor 110, to ground through the alternate contact of the depressed key and the particular inductance and capacity connected thereto. 20 The other circuit may be traced from ground, through the upper secondary winding of the transformer 501, battery, conductor 506, thence in parallel to the common conductor 504, through relay 518 and condenser 523 in series, relay 519 and condenser 524 in series, relay 520 and condenser 525 in series, relay 521 and condenser 526 in series, relay 522 and condenser 527 in series, 25 and left-hand winding of relay 502, then through the upper contact of sequence switch 30 spring 323, brush 313, terminal 318, conductor 325, lower contact of sequence switch spring 206, conductor 205, brush 104, terminal 107, conductor 111, normal contacts of 35 keys Nos. 5 to 9 inclusive, conductor 110, to ground through the alternate contact of the depressed key and the inductance and capacity connected thereto.

40 Each of the sources of current f^1 to f^5 inclusive, induces an electromotive force of a corresponding frequency in each of these circuits, and each of these induced electromotive forces causes a current of a corresponding frequency to flow through each circuit as above described.

The impedance of the first traced circuit is so designed, however, that none of the currents therein operates any one of the relays 508 to 512 inclusive. The impedance of the second traced circuit is such, however, as to produce resonance for one of the electromotive forces induced therein, and as a result sufficient current of the proper frequency flows through this circuit to operate the particular one of the relays 518 to 522 which is operated by current of such frequency. This impedance of the second traced circuit is of such a value, however, 50 as to prevent sufficient current of any other frequency from flowing to operate any other one of the relays 518 to 522 inclusive.

By depressing any other one of the keys Nos. 0 to 4 inclusive, a different inductance 55 and capacity is included in each of the above

traced circuits. The impedance of the last traced circuit is changed each time a different key is depressed so as to produce resonance for a different one of the electromotive forces induced in the upper winding of the 70 transformer 501. Sufficient current of the corresponding frequency then flows through this circuit and operates the particular one of the relays 518 to 522 inclusive, which operates at such frequency. As before, the 75 new impedance of this circuit and the impedance of the first traced circuit, which is changed each time a different one of keys Nos. 0 to 4 inclusive is depressed, are so designed that none of the other nine alternating current relays operate.

Therefore, it will be observed that the depression of any one of the keys Nos. 0 to 9 inclusive will operate a certain one of the relays 508 to 512 inclusive or a certain one of the relays 518 to 522 inclusive. It should also be observed that each time any one of the keys is depressed, there is always a circuit completed through battery for the winding of the relay 502, and 85 therefore this relay remains energized.

For this description it will be assumed that when key No. 0 is depressed, relay 522 is operated, when key No. 1 is depressed, relay 521 is operated, and in a similar manner when the keys Nos. 2 to 9 inclusive are depressed successively relays 520, 519, 518, 512, 511, 510, 509 and 508 respectively are operated.

We will also assume that the number corresponding to the telephone of the party wanted is 05944, the digit 0 representing the office in which the wanted party's line terminates. The calling subscriber thereupon presses keys Nos. 0, 5, 9, 4 and 4 in 100 105 succession.

In response to the depression of key No. 0, sufficient current of the proper frequency flows through the winding of relay 522 to cause it to attract its armature and complete 105 a circuit from grounded battery, through winding of relay 528, armature and front contact of relay 522, conductor 529, upper right-hand contact of sequence switch spring 530, winding of relay 531 to ground. Relay 110 531 becomes energized and closes a locking circuit for itself from grounded battery through contact of sequence switch spring 327, conductors 328 and 532, left-hand armature and contact of relay 531, winding 115 of relay 531 to ground.

Relay 528 also is energized in the above traced energizing circuit of relay 531 and closes a circuit from grounded battery, through winding of the slow-to-release relay 533, armature and front contact of relay 528 to ground. As soon as the key 120 125 No. 0 is released the relay 522 deenergizes and opens the circuit of relay 528. Relay 528 deenergizes and closes the following 130

5 circuit before relay 533 has time to deenergize: grounded battery through power magnet of sequence switch 500, armature and contact of relay 533, armature and back contact of relay 528 to ground. Sequence switch 500 is thereupon moved out of position 1 and into position 2.

6 In response to the depression of key No. 5, sufficient current of the proper frequency 10 flows through the winding of relay 512 to cause it to attract its armature and close a circuit from grounded battery, through the winding of relay 528, armature and contact of relay 512, conductor 534, upper left-hand contact of sequence switch spring 535, winding of relay 536 to ground. Relay 536 becomes energized and closes a locking 15 circuit for itself from grounded battery, through contact of sequence switch spring 327, conductors 328 and 537, left-hand armature and contact of relay 536, winding of relay 536 to ground. Relay 528 closes the above traced circuit for relay 533 so that when the key No. 5 is released, the 20 above traced circuit for the power magnet of sequence switch 500 is closed to move the sequence switch 500 out of position 2 and into position 3.

25 In response to the depression of key No. 9, sufficient current of the proper frequency 30 flows through the winding of relay 508 to cause it to attract its armature and close a circuit from grounded battery through the winding of relay 528, armature and contact of relay 508, conductor 538, lower left-hand contact of sequence switch spring 539, winding of relay 540, to ground. Relay 540 becomes energized and closes a locking 35 circuit for itself from grounded battery, through the contact of sequence switch spring 327, conductors 328 and 541, left-hand armature and front contact of relay 540, winding of relay 540 to ground. Relay 528 energizes in the above traced circuit 40 and closes the energizing circuit of relay 533. After the key No. 9 is released, the above traced circuit for the power magnet 45 of sequence switch 500 is closed to move the sequence switch out of position 3 and into position 4.

50 In response to the first depression of key No. 4, sufficient current of the proper frequency flows through the winding of relay 518 to cause it to attract its armature and 55 close a circuit from grounded battery, through the winding of relay 528, armature and contact of relay 518, conductor 542, lower right-hand contact of sequence switch 543, winding of relay 544 to ground. Relay 528 becomes energized and closes the 60 above traced circuit for relay 533. Relay 544 also becomes energized and closes a locking circuit for itself from grounded battery, through contact of sequence switch 65 spring 327, conductors 328 and 545, left-

hand armature and contact of relay 544, winding of relay 544 to ground. When the key No. 4 is released after its first depression the above traced circuit for the power magnet of sequence switch 500 is closed to 70 move the sequence switch out of position 4 and into position 5.

75 In response to the second depression of the key No. 4 sufficient current of the proper frequency again flows through the winding of relay 518 to cause it to attract its armature. A circuit is now closed from grounded battery, through winding of relay 528, armature and contact of relay 518, conductor 542, upper contact of sequence switch spring 80 543, winding of relay 546 to ground. Relay 528 becomes energized and closes the above traced circuit for relay 533. Relay 546 also becomes energized and closes a locking 85 circuit for itself from grounded battery, through contact of sequence switch spring 327, conductors 328 and 547, left-hand armature and contact of relay 546, winding of relay 546 to ground. When the key No. 4 is released after its second depression the 90 above traced circuit for the power magnet of sequence switch 500 is closed to move the sequence switch out of position 5 and into position 6.

95 When relay 546 became energized a circuit was completed from grounded battery, through the windings of the power magnets of registers 400, 410, 420, 430 and 440 in parallel, right-hand armature and back contacts of relays 450, 451, 452, 453 and 454 in parallel, conductor 455, right-hand armature and front contacts of relay 546 to ground.

100 Each of these registers will thereupon move from the position in which it has now been found to a position determined by the 105 keys Nos. 0, 5, 9, 4, respectively. In the case of office register 400, the movement thereof will continue until the zero position is reached, at which time a circuit is completed from grounded battery, through the 110 winding of relay 450, lower contact of register spring 401, conductor 402, right-hand armature and contact of relay 531 to ground. Relay 450 attracts its armatures, thereby 115 opening the energizing circuit for the power magnet of register 400. At the same time a circuit is established from grounded battery, through the winding of relay 556, left-hand armature and front contact of relay 450, common conductor 457, and thence in one 120 direction through the winding of relay 458 to ground, and in the other direction through the left-hand armatures and back contacts of relays 451, 452, 453 and 454 in parallel to ground.

125 It will be noted that relay 556 is energized in this circuit, but that relay 458 will be short-circuited until each of the left-hand armatures of relays 451, 452, 453 and 454 have been attracted.

The setting of the thousands register, the hundreds register, the tens register, and the units register is similar to that described in connection with the setting of the office register, and these settings take place simultaneously. When all are completed the registers will be in the following positions: the office register in position 0, the thousands register in position 5, the hundreds register 5 in position 9, the tens register in position 4 and the units register in position 4.

At this time also the shunt around the winding of relay 458 is removed and therefore sufficient current will flow through its 10 winding to cause its energization. A circuit is then established from grounded battery, through the power magnet of sequence switch 300, right-hand contact of sequence switch spring 329, conductor 330, armature and contact of relay 458 to ground for moving the sequence switch 300 out of position 3 and into position 4.

When the sequence switch 300 leaves position 3 the holding circuits of relays 531, 536, 25 540, 544 and 546 are opened. These relays deenergize and open the circuit of relays 450, 451, 452, 453 and 454 respectively. Each of these last mentioned relays retracts 30 its armatures and in so doing causes the de- energization of both relays 556 and 458.

Relay 556, in retracting its armature, closes a circuit from grounded battery, through the power magnet of sequence switch 300, left-hand contact of sequence 35 switch spring 329, conductor 331, armature and back contact of relay 556 to ground, for moving the sequence switch 300 out of position 4 and into position 5.

While the sequence switch 300 was in position 4, a circuit was completed from grounded battery, through the power magnet of sequence switch 200, lower contact of sequence switch spring 209, conductor 332, terminal 316, brush 311, contact of sequence 45 switch spring 333 to ground, for moving the sequence switch 200 out of position 2 and into position 3.

When sequence switch 300 reaches position 5, the fundamental circuit is completed 50 and extends from grounded battery, through winding of relay 212, upper contact of sequence switch spring 213, conductors 214 and 325, terminal 318, brush 313, lower contact of sequence switch spring 323, outer 55 armature and back contact of relay O, winding of stepping relay 334, lower contact of sequence switch spring 322, to ground.

Relay 212 becomes energized and establishes through its right-hand armature and 60 front contact and the lower left-hand contact of sequence switch spring 213, a locking circuit for itself to ground over the above traced circuit. Relay 212 also closes a circuit from grounded battery, through the 65 power magnet of sequence switch 200, upper

right-hand contact of sequence switch spring 215, left-hand armature and front contact of relay 212, to ground, for moving the sequence switch 200 out of position 3 and into position 4.

In position 4 of sequence switch 200, a circuit is closed from grounded battery, through the winding of updrive magnet 216, contact of sequence switch spring 217, left-hand armature and front contact of relay 75 212 to ground. Magnet 216 attracts its armature and in so doing, presses the driving ribbon 218 against the constantly rotating roller 219, whereby the brush carriage 80 220 is elevated. As the brush 221 passes over the commutator 222 the stepping relay 334 is intermittently deenergized and energized as hereinafter described.

Upon the initial energization of relay 334, a circuit is closed from grounded battery, 85 through winding of counting relay O, conductor 335, lower contact of register spring 403, conductor 336, upper left-hand contact of sequence switch spring 337, armature and contact of relay 334 to ground. Counting 90 relay O is thereupon energized and closes a circuit from grounded battery, through windings of counting relays O and O', armature and contact of counting relay O, right-hand contact of sequence switch spring 95 328 to ground. Counting relay O', however, is shunted through the conductor 335 over the circuit previously described, and therefore does not energize until relay 334 deenergizes.

When the commutator brush 221 passes over the first conducting segment of commutator 222, a shunt circuit is closed around the winding of relay 334 as follows: grounded battery, through the winding of relay 105 212, right-hand armature and contact of relay 212, lower right-hand contact of sequence switch spring 913, conductor 223, commutator 222, brush 221, to ground. Relay 334 thereupon deenergizes and this results in the energization of counting relay 110 O'. Counting relay O', by attracting its outer left-hand armature, opens the fundamental circuit, and removes the ground at the lower left-hand contact of sequence 115 switch spring 322 from the circuit leading to relay 212. Therefore as soon as the brush 221 reaches an insulating segment of the commutator 222, the relay 212 becomes deenergized. As the relay 212 deenergizes it 120 opens the circuit of the updrive magnet 216, whereupon the brushes 224, 225 and 226 secured to the brush carriage 220 come to rest at the bottom of the selected group of trunks. The deenergization of relay 212 also closes 125 a circuit from grounded battery, through power magnet of sequence switch 200, upper left-hand contact of sequence switch spring 215, left-hand armature and back contact of relay 212 to ground, for moving the sequence 130

switch 200 out of position 4 and into position 5.

When the counting relay O' became energized it also closed a circuit from grounded battery through the power magnet of sequence switch 300, inner armature and contact of counting relay O', left-hand contact of sequence switch spring 338 to ground, for moving the sequence switch 300 out of position 5 and into position 7. When the sequence switch 300 leaves position 5, the circuit for energizing the counting relays is opened at the right-hand contact of sequence switch spring 338.

When position 5 of sequence switch 200 is reached, a circuit is closed from grounded battery, through winding of relay 212, upper contact of sequence switch spring 213, left-hand contacts of sequence switch springs 227 to ground. Relay 212 becomes energized, and is held energized through a circuit leading from grounded terminal 228 of busy trunks of the group to which the brush carriage 220 has been directed, through brush 224, upper contact of sequence switch spring 227, and thence to grounded battery over the circuit previously traced. The energization of relay 212 closes a circuit from grounded battery, through the power magnet of sequence switch 200, upper right-hand contact of sequence switch spring 215, left-hand armature and front contact of relay 212 to ground, for moving the sequence switch 200 out of position 5 and into position 6.

In position 6 of the sequence switch 200, a circuit is established from grounded battery, through the winding of the updrive magnet 216, contact of sequence switch spring 217, left-hand armature and front contact of relay 212 to ground. Magnet 216 attracts its armature and causes the elevation of the brush carriage 220. This elevation continues until the brush 224 encounters the terminal 228 of an idle trunk, whereupon the holding circuit for relay 212 is opened. This results in the deenergization of relay 212, whereupon the circuit of magnet 216 is opened, thereby causing the brushes 224, 225 and 226 to come to rest on the terminals 228, 229 and 230 of an idle trunk.

The deenergization of relay 212 also closes a circuit from grounded battery, through the power magnet of sequence switch 200, upper left-hand contact of sequence switch spring 215, left-hand armature and back contact of relay 212 to ground, for moving the sequence switch 200 out of position 6 and into position 11.

When the sequence switch 200 reaches position 7, a circuit is closed from ground, through the lower contact of sequence switch spring 227, brush 224, and the terminal 228, thus rendering the selected trunk busy.

A fundamental circuit is now completed

from grounded battery at the selected switch, thence over conductor 231, terminal 230, brush 226, lower contact of sequence switch spring 233, conductors 235, 214 and 325, terminal 318, brush 313, lower contact of sequence switch spring 323, outer armature and contact of counting relay O', winding of relay 334, lower right-hand contact of sequence switch spring 322, brush 312, terminal 317, conductors 324 and 236, right-hand contact of sequence switch spring 234, brush 225, terminal 229, conductor 232 to ground at the selected switch. Through any appropriate means at the selected switch, the switch power magnet thereat will be energized and brush selection may take place in the well known manner. The switch in its movement will cause deenergization of relay 334, by means of a commutator similar to 222 at the district selector switch.

Upon the energization of relay 334, a circuit is closed from grounded battery, through winding of counting relay 2, armature and back contact of counting relay 2', conductor 339, upper left-hand contact of register spring 411, conductor 340, upper right-hand contact of sequence switch spring 337, armature and contact of relay 334 to ground.

Counting relay 2 energizes and prepares an energizing circuit for counting relay 2'. The counting relays are then operated in the well-known manner. As soon as counting relay O' becomes energized it opens the fundamental circuit, and brings to a close the first cycle of operations at the second selector switch. The energization of counting relay O' also closes a circuit from grounded battery, through power magnet of sequence switch 300, inner armature and contact of counting relay O', left-hand contact of sequence switch spring 338 to ground, and the sequence switch moves from position 7 to position 9. In passing from position 7 to position 9, the sequence switch 300 interrupts, at the right-hand contact of spring 338, the holding circuits for the counting relays.

In position 9 of the sequence switch 300, the fundamental circuit is again closed through to the second selector switch and group selection thereat will now take place. As the switch shaft is elevated, current through the relay 334 will be interrupted by means of a shunt circuit in the well-known manner. Upon the initial energization of relay 334, a circuit is closed from grounded battery, winding of counting relay 3, armature and back contact of counting relay 3', conductors 341 and 460, upper contact of sequence switch spring 421, upper contact of sequence switch spring 412, conductor 342, lower right-hand contact of sequence switch spring 337, armature and contact of relay 130

384 to ground. Each subsequent deenergization and energization of relay 334 actuates the counting relays in the well-known manner. As soon as the counting relay O' energizes, it opens the fundamental circuit, thus ending the second cycle of operations and stopping the third set of brushes at the second selector switch at the bottom of the fourth group of trunk terminals. The 10 brushes of the selected set will now be caused to hunt for terminals associated with an idle final selector switch.

The energization of counting relay O' also closes a circuit from grounded battery, 15 through power magnet of sequence switch 300, inner armature and contact of counting relay O', left-hand contact of sequence switch spring 338 to ground, for moving the sequence switch out of position 9 and into 20 position 11. The holding circuit for the counting relays is interrupted at the right-hand contact of sequence switch spring 338 as before.

As soon as the second selector finds an 25 idle trunk, the fundamental circuit is closed to the final selector switch associated with such idle trunk. Brush selection at the final selector switch will now take place. As the final selector switch shaft is elevated, 30 current through 334 will be interrupted by means of a shunt circuit in the well-known manner. Upon the initial energization of relay 334, a circuit is closed from grounded battery, through winding of counting relay 35 4, armature and back contact of counting relay 4', conductors 343 and 461, right-hand contact of register spring 422, conductor 344, lower left-hand contact of sequence switch spring 337, armature and contact of 40 relay 334 to ground. Each subsequent deenergization and energization of relay 334 actuates the counting relays in the well-known manner.

As soon as the counting relay O' becomes 45 energized, the fundamental circuit is interrupted, thus terminating the brush selection at the final selector switch. The energization of counting relay O' also completes a circuit from grounded battery, 50 through power magnet of sequence switch 300, inner armature and contact of counting relay O', left-hand contact of sequence switch spring 338 to ground, for moving the sequence switch out of position 11 and into 55 position 13. When the sequence switch leaves position 11, the holding circuit for the counting relays is opened as before.

When the sequence switch 300 reaches 60 position 13, the fundamental circuit is again closed through to the final selector switch. Tens selection thereat now takes place.

Upon the energization of relay 334 when the fundamental circuit is closed, a circuit is completed from grounded battery, 65 through counting relay 4, armature and

back contact of counting relay 4', conductors 343 and 462, lower right-hand contact of register spring 431, conductor 345, right-hand contact of sequence switch spring 346, armature and contact of relay 334 to 70 ground. The counting relays are then actuated in the well-known manner.

As soon as counting relay O' is energized, the fundamental circuit is opened, thus selecting the tens group of terminals in which 75 the called subscriber's line terminals are located. The energization of counting relay O' also completes a circuit from grounded battery through the power magnet of sequence switch 300, inner armature and contact of counting relay O', left-hand contact of sequence switch spring 338 to ground, for moving the sequence switch out of position 13, and into position 15. The holding circuit of the counting relays is open at the 80 right-hand contact of sequence switch spring 338 when the sequence switch 300 leaves position 13.

When the sequence switch 300 reaches position 15, the fundamental circuit is again 90 closed, and units selection now takes place. Upon the energization of relay 334 by the closing of the fundamental circuit, a circuit is closed from grounded battery, through 95 counting relay 4, armature and back contact of counting relay 4', conductors 343 and 463, lower right-hand contact of sequence switch spring 441, conductor 347, left-hand contact of sequence switch spring 346, armature and contact of relay 334 to 100 ground. The counting relays will be energized in the well-known manner until the counting relay O' is energized. Counting relay O' interrupts the fundamental circuit, thus determining the terminals on which 105 the brushes of the final selector switch shall rest. The energization of counting relay O' also closes a circuit from grounded battery, through power magnet of sequence switch 300, inner armature and contact of counting 110 relay O', left-hand contact of sequence switch spring 338 to ground, for moving the sequence switch out of position 15 and into position 16.

In position 16 of sequence switch 300, a 115 circuit is completed from grounded battery, through power magnet of sequence switch 200, lower contact of sequence switch spring 209, conductor 332, terminal 316, brush 311, contact of sequence switch spring 333 to 120 ground, for moving the sequence switch 200 out of position 11 and into position 16.

Sequence switch 200 in moving out of position 11, opens at the upper right-hand contact of sequence switch spring 210, the holding circuit of relay 305. Relay 305 is thereupon deenergized, and completes a circuit from grounded battery, through power magnet of sequence switch 300, lower right-hand contact of sequence switch spring 301, right- 125 130

hand armature and back contact of relay 305 to ground, for moving the sequence switch 300 out of position 16 and into position 17.

In position 17 of sequence switch 300, a circuit is closed from grounded battery through winding of downdrive magnet 348, contact of sequence switch spring 349 to ground. Magnet 348 attracts its armature, and thereby presses the driving ribbon 306 10 against the constantly rotating roller 350, whereby the brush carriage 308 is returned to its normal position.

When this normal position has been reached, a circuit is closed from grounded battery, through power magnet of sequence switch 300, upper left-hand contact of sequence switch spring 301, normal conducting segment 351, brush 352, to ground, for moving the sequence switch 300 into its normal position. The trunk finder is now ready to perform the functions heretofore described in connection with any other trunk circuit which may be selected by the initiation of another call.

25 The subscribers will now be connected for conversation. When the calling subscriber at substation 100 places his receiver on the switchhook at the end of the conversation, the previously traced circuit through relay 302 is opened, and when it becomes deenergized, it opens the circuit of relay 208. Relay 208 deenergizes and closes a circuit from grounded battery, through power magnet of sequence switch 200, upper right-hand contact of sequence switch spring 209, right-hand armature and back contact of relay 208 to ground, for moving the sequence switch 200 out of position 16 and into position 18.

40 The deenergization of relay 202 also opens the circuit of relay 112, whereupon the release of the finder switch 101 takes place in the well-known manner.

In position 18 of sequence switch 200, a circuit is completed from grounded battery, winding of downdrive magnet 237, contact of sequence switch spring 238 to ground. Magnet 237 by attracting its armature presses the driving ribbon 218 into engagement with the constantly rotating roller 239 to return the district selector switch shaft to its normal position. When the switch reaches such position, a circuit is closed from grounded battery, through power magnet of sequence switch 200, lower contact of sequence switch spring 215, conductor 240, normal conducting segment 241, brush 221, to ground for moving the sequence switch out of position 18 and into its normal position.

If the calling subscriber should abandon the call at any time after he has started operating his call transmitter, but before he has transmitted the complete number, release will take place as follows: When the

calling subscriber places his receiver upon the switchhook, the circuit of relay 502 will be opened (as sequence switch 300 will be in position 3 and sequence switch 200 in position 2 at this time). The continued de-energization of relay 502 causes the deenergization of relay 507. A circuit is then closed from grounded battery, through power magnet of sequence switch 500, contact of sequence switch spring 548, right-hand armature and contact of relay 507, armature and back contact of relay 502 to ground, for moving the sequence switch 500 into its normal position. The deenergization of relay 507 also closes a circuit from grounded battery through winding of relay 326, contact of sequence switch spring 353, conductor 354, left-hand armature and back contact of relay 326 to ground. Relay 326 becomes energized and closes a locking circuit for itself from grounded battery, through winding of relay 326, right-hand armature and contact of relay 326, contact of sequence switch spring 355 to ground. The energization of relay 326 also closes a circuit from grounded battery, through power magnet of sequence switch 300, contact of sequence switch spring 356, left-hand armature and contact of relay 326 to ground, for moving the sequence switch 300 out of position 3 and into position 16.

While the sequence switch 300 is moving through position 4, the above traced circuit is closed at the contact of sequence switch spring 333 for moving the sequence switch 200 out of position 2 and into position 3. Relay 208, which was connected to grounded battery through the contact of sequence switch spring 211 in position 2 of sequence switch 200, now becomes deenergized and closes the above traced circuit for moving the sequence switch 200 into position 18. The trunk finder switch and the district selector switch are now returned to their normal position in the manner described.

What is claimed is:

1. In a telephone system, a circuit, variably operable automatic switches, a plurality of sources of current connected to said circuit, each being of a different frequency, electromagnetic devices included in said circuit for controlling the variable operation of said switches, and means for placing said circuit in condition of resonance for each one of said sources of current to selectively operate said electromagnetic devices.

2. In a telephone system, variably operable automatic switches, a circuit, a plurality of sources of alternating current connected thereto, means for varying the impedance of said circuit to vary the currents produced in said circuit by said sources of current, and means selectively operated by said various currents for controlling the variable operation of said switches.

3. In a telephone system, a pair of conductors, a plurality of sources of alternating current connected to each conductor, electromagnetic devices connected to each of 5 said conductors, a plurality of different impedances, and means for closing a circuit through either of said conductors and any one of a plurality of different impedances to place such circuit in condition of resonance for one of said sources of current to 10 selectively operate said electromagnetic devices.
4. In a telephone system, automatic switches, a pair of conductors, a plurality of 15 sources of alternating current connected to each conductor, electromagnetic devices connected to each of said conductors for controlling the operation of said switches, a plurality of different impedances, and means 20 for closing a circuit through either of said conductors and any one of a plurality of different impedances to place said circuit in condition of resonance for one of said sources of current to selectively operate said 25 electromagnetic devices.
5. In a telephone system, a pair of conductors, a plurality of sources of current connected to each conductor, electromagnetic devices connected to each of said conductors, a plurality of different impedances, means for closing a circuit including said 30 conductors in series, said electromagnetic devices being non-responsive to the current in said circuit, and means for closing a circuit through either of said conductors and any one of said impedances to place such 35 last mentioned circuit in condition of resonance for one of said sources of current to selectively operate said electromagnetic devices.
6. In a telephone system, automatic switches, a plurality of conductors, a plurality of sources of current connected to each conductor, electromagnetic devices connected to each of said conductors for controlling the operation of said switches, a plurality of different impedances, means for closing a circuit including said conductors in series, said electromagnetic devices being 45 non-responsive to the current in said circuit, and means for closing a circuit through 50

either of said conductors and any one of said impedances to place such last mentioned circuit in condition of resonance for one of said sources of current to selectively 55 operate said electromagnetic devices.

7. In a telephone system, a pair of conductors, a plurality of sources of current connected to each conductor, electromagnetic devices connected to each of said conductors, means for closing a circuit through either of said conductors, and means in said circuit for placing said circuit in condition of resonance for one of said sources of current to selectively operate the electromagnetic 60 devices connected to the conductor through which the circuit is closed.

8. In a telephone system, a telephone line, automatic switches, a plurality of sources of current, each of a different frequency, means for connecting said sources of current to said line, and means for closing through said line resonating circuits for each one of said sources of current to selectively control the operation of said 75 switches.

9. In a telephone system, a telephone line, automatic switches, a plurality of sources of current, each of said sources of current being of a different frequency, means for connecting said sources of current to said line, means for closing through said line resonating circuits for each of said sources of current, and means selectively operated by the current in said resonating circuits 85 for controlling the operation of said switches.

10. In a telephone system, a subscriber's line, automatic switches, a plurality of sources of current, each of said sources of current being of a different frequency, means for connecting said sources of current to said line, means under the control of said subscriber for closing resonating circuits through said line for each of said 90 sources of current, and means selectively operated by the current in said resonating circuits for controlling the operation of said switches.

In witness whereof I hereunto subscribe 100 my name this 6th day of April, A. D. 1918.
JAMES L. McQUARRIE.
